US00D825504S

(12) **United States Design Patent** (10) **Patent No.:** **US D825,504 S**
Zhang et al. (45) **Date of Patent:** **** Aug. 14, 2018**

(54) **TARGET PROFILE FOR A PHYSICAL VAPOR DEPOSITION CHAMBER TARGET**

(71) Applicant: **APPLIED MATERIALS, INC.**, Santa Clara, CA (US)

(72) Inventors: **Fuhong Zhang**, San Jose, CA (US); **William Johanson**, Gilroy, CA (US); **Yu Liu**, Campbell, CA (US); **Adolph Miller Allen**, Oakland, CA (US); **Brij Datta**, Cupertino, CA (US); **Keith A. Miller**, Mountain View, CA (US)

(73) Assignee: **APPLIED MATERIALS, INC.**, Santa Clara, CA (US)

(**) Term: **15 Years**

(21) Appl. No.: **29/610,166**

(22) Filed: **Jul. 10, 2017**

(57) **CLAIM**

The ornamental design for a target profile for a physical vapor deposition chamber target, as shown and described.

DESCRIPTION

FIG. 1 is a perspective view of a target profile for a physical vapor deposition chamber target, showing my new design; FIG. 2 is a top plan view thereof; FIG. 3 is a bottom plan view thereof; FIG. 4 is a left side elevation view thereof; FIG. 5 is a right side elevation view thereof; FIG. 6 is a back elevation view thereof; FIG. 7 is a front elevation view thereof; and, FIG. 8 is a cross sectional view taken along line 8-8 of FIG. 2.

The dashed lines in FIGS. 1-8 represent disclaimed matter that forms no part of the claimed design.

1 Claim, 6 Drawing Sheets
